UNITED STATES PATENT OFFICE.

WILLIAM D. FULLER, OF SPRINGFIELD, OHIO, ASSIGNOR, BY MESNE ASSIGNMENTS,
TO ELLIOTT COMPANY, OF PITTSBURGH, PENNSYLVANIA, A CORPORATION OF
PENNSYLVANIA.

TUBE-CLEANER.

1,185,083.

Specification of Letters Patent. Patented May 30, 1916.

Application filed October 29, 1915. Serial No. 58,699.

To all whom it may concern:

Be it known that I, WILLIAM D. FULLER, a citizen of the United States, residing at Springfield, in the county of Clark and State 5 of Ohio, have invented certain new and useful Improvements in Tube-Cleaners, of which the following is a specification, reference being had therein to the accompanying drawings.

10 My invention relates to tube cleaners and more particularly to rotary tube cleaners operated at a high speed for heavy duty in cleaning the hard scale from water tube boilers.

15 Such service is very severe and the object of my invention is to provide an improved cleaner simple, efficient and durable that will withstand the shocks and jars incident to this heavy duty.

20 My attention has been especially directed to improving means for pivoting the cutter carrying arms to the body whereby freedom of movement, ease of assembling and disassembling and durability are combined.

25 With these and other objects in view my invention consists of the constructions and combinations hereinafter described and set forth in the claims.

In the accompanying drawings which 30 form a part of this specification Figure 1 is a longitudinal section of a tube cleaner embodying my invention taken on the line 1—1 of Fig. 3. Fig. 2 is a like section taken on the line 2—2 of Fig. 3 and Fig. 3 is a 35 cross-section taken on the line 3—3 of Fig. 1.

Like numerals represent the same parts in the several views.

In the drawings 1 represents a body having 40 a front head 2 and a rear head 3, the respective heads having a plurality of oppositely disposed bores 4. Said heads are cut away so as to leave a lateral opening 5 for each of said bores and to form stops 6 and 45 7. A plurality of pairs of arms 8 are provided and each pair is joined together by a pivotal portion 9 preferably formed integrally therewith. The pivotal portions 9 of the arms 8 are introduced from the rear 50 through the bores 4 in the rear head and extend into the oppositely disposed bores of the front head. The arms project through the lateral openings 5 in the bores and are free to swing between the limits of the stops 55 6 and 7.

The bores 4 in the front head terminate within the head and form stops 10 to prevent forward movement of the arms and the arms are held against rearward movement by a coupling member 11 screw-threaded to a 60 rearward extension 12 of the body and engaging the pivotal portions 9 of the arms. The screw-threaded end of the coupling extends beyond the extension 12 of the body for attachment of the driving shaft. Bolts 65 13 having heads 14 extend through openings in the free end of the front arm of each pair of arms and are screw-threaded to the rear arms as shown. Rotary cutters 15 are mounted on the bolts between the arms and also between the front head 2 and the bolt heads 14. The joining of each pair of arms by a portion forming a pivot therefor gives a strong, simple construction and it will be further noted the lateral openings 5 permit 70 each pair of arms to be spaced farther apart so that a greater number of cutters can be employed between the heads thus giving a greater cutting capacity in a head of given length. To shorten the head and maintain 75 this cutting capacity is especially desirable when employed in cleaning bent tubes.

Having thus described my invention I claim—

1. In a tube cleaner, a rotary body having 85 a longitudinally extending bore with a lateral opening throughout its length, an arm pivoted in and held from radial movement by the walls of said bore and projecting through said lateral opening and cutters 90 mounted on said arm, substantially as described.

2. In a tube cleaner, a rotary body having a plurality of longitudinally extending bores, each bore being of uniform diameter and having a lateral opening throughout its length, arms pivoted in and held from radial movement by the walls of said bore and projecting through said lateral openings, cutters mounted on said arms and 95 means to keep said arms from longitudinal movement, substantially as described.

3. In a tube cleaner, a rotary body having a plurality of longitudinally extending bores with lateral openings throughout their 100 length, arms having pivotal portions adapted to turn in and to be held from radial movement by the walls of said bores, with the arms projecting through said lateral openings, permitting the arms to swing 110

within the limits of said openings, cutters carried by the free ends of said arms and means to prevent the longitudinal movement of said arms, substantially as described.

4. In a tube cleaner, a rotary body having front and rear heads formed integrally therewith with oppositely disposed bores in the respective heads, each of said bores being 10 of uniform diameter and having a lateral opening throughout its length, arms having pivotal portions formed integrally therewith, the opposite ends of said portions being pivoted in and held from radial 15 movement by the oppositely disposed bores of the respective heads, said arms projecting through and limited in their swinging movement by said lateral openings, cutters mounted on the free ends of said arms 20 and means to prevent the longitudinal movement of said arms, substantially as described.

5. In a tube cleaner, a rotary body having a longitudinally extending bore with a 25 lateral opening, an arm having a pivotal portion formed along its inner edge adapted to fit and be held from radial movement

by the wall of said bore, said arm projecting through said lateral opening and having cutters on its outer or free end and 30 means to prevent the longitudinal movement of said arm, substantially as described.

6. In a tube cleaner, a rotary body having front and rear heads with a plurality of oppositely disposed bores in the respective heads, each of said bores having a lateral opening, a plurality of pairs of arms, each pair being joined by a pivotal portion adapted to fit and be held from radial movement by the walls of the oppositely disposed bores in the respective heads, said arms projecting through said lateral openings and having cutters mounted on the free ends thereof and means to prevent the longitudinal movement of said arms, substantially as described.

In testimony whereof I have hereunto affixed my signature in the presence of two witnesses.

WILLIAM D. FULLER.
